UNITED STATES PATENT OFFICE.

DAVID F. VAUGHAN, OF RIVERTON, NEW JERSEY.

TAMPING-TOOL.

1,260,602.

Specification of Letters Patent. Patented Mar. 26, 1918.

Application filed July 26, 1917. Serial No. 182,876.

To all whom it may concern:

Be it known that I, DAVID F. VAUGHAN, a citizen of the United States, residing at Riverton, in the county of Burlington and 5 State of New Jersey, have invented certain new and useful Improvements in Tamping-Tools, of which the following is a specification.

My invention relates to improvements in 10 tamping tools for use in tamping railroad ballast and analogous uses.

Tamping tools for this purpose are usually in the form of picks and bars operated by hand or by suitable mechanical devices, the 15 picks and bars having substantially flat, impact, end portions adapted to strike against the material being tamped.

Heretofore tamping tools have been objectionable because, when in use, the impact 20 end portions thereof quickly assume a sharp, rounded or pointed form due to wear occasioned by the friction of the tools against the broken stones, gravel or other material being tamped. This quickly decreases the 25 efficiency of the tools, as the impact end portions thus worn enter between the pieces of ballast material and separate them instead of driving them into the desired position during the tamping operation, and require 30 the impact end portions to be reforged to produce fresh, substantially flat, impact portions thereon. This requirement is not only accompanied by the great objection that the 35 body member of the tool, having the impact end portion, gradually grows shorter under successive reforging operations, but also by the further objection that much time is lost by the tools remaining out of service before, during and after the reforging operations, 40 as it is necessary to send them to suitable shops for this purpose.

The object of my invention is to overcome or greatly lessen the objections above set forth; and I accomplish my object by 45 the provision of a tamping tool of novel, simple and efficient construction: first, having an impact end portion which in service can not be worn into the objectionable sharp, rounded or pointed form; and, second, having 50 the impact end portion thereof formed on an impact member which is removably engaged with the operated body member of the tool and which, when it wears down, may

be readily removed from the body member and substituted by a new one at comparatively little expense. 55

With this and related objects in view, my invented tool consists of the elements and the combinations of them hereinafter described and claimed. 60

In the accompanying drawings, illustrating my invention:

Figure 1 is a side view of a tamping tool embodying my invention and showing the body member thereof in the form of a hand 65 bar.

Fig. 2 is a side view of a tamping tool embodying my invention and showing the body member thereof in the form of a pick.

Fig. 3 is a side view of the end portion 70 of the body member of the tool which receives the impact member, having the impact member removed therefrom.

Fig. 4 is a face view of the part shown in Fig. 3.

Fig. 5 is a bottom view of the part shown in Fig. 3.

Fig. 6 is a view similar to Fig. 5, showing the impact member applied to the body member. 80

Fig. 7 is a perspective view of the impact member removed from the body member.

Fig. 8 is a view similar to Fig. 4, showing the impact member applied to the body member. 85

Fig. 9 is a view of the parts shown in Fig. 8, showing the impact member in section.

Fig. 10 is an end view of the impact member detached from the body member. 90

Fig. 11 is an end view of a modified form of the impact member.

Fig. 12 is a view similar to Fig. 8, showing the modified form of the impact member illustrated in Fig. 11. 95

Referring to the drawings, 2 designates the body member which may be of any suitable shape and size for its intended purpose to be operated either by hand or by power devices during the tamping operation. 100

The body member 2 has an end portion 3 which is adapted to be driven down toward the material being tamped; and this end portion 3 is provided with an impact member 4 which is adapted to strike against the 105 said material, during the tamping opera-

tion, and which is preferably made separate and detachable from the body member 2, as will be hereinafter explained.

The end portion 3 of the body member 2 is reduced, as illustrated, providing a projecting tongue 5 to receive the impact member 4, and providing shoulders 6 at the base of the tongue 5. The member 4 is formed of suitable hard, resilient metal adapted when sprung from a normal condition to continue to tend to resume said normal condition, for a purpose hereinafter explained.

The impact member 4 is preferably made in the form of a band and shaped to fit closely around the projecting tongue 5 when it is driven on to the same; and, as illustrated in Figs. 6, 7 and 10, one side of the member 4 is split, at 7; and, in the normal condition of the member 4, as shown in Figs. 7 and 10, the free arms 8, formed by the split side of the member 4, are inclined inwardly, so that the normal distance between them and the opposite side of the member 4 will be less than the thickness of the projecting tongue 5 of the body member 2. When the impact member 4 is driven on to the tongue 5, the arms 8 will be sprung outwardly by the tongue 5 to a position parallel with the opposite side of the member 4 and with the face of the tongue 5 against which they bear, so that, after the member 4 has been driven on to the tongue 5, as shown in Figs. 1, 2, 6, 8 and 9, the arms 8, in tending to resume their said normal or inwardly inclined condition, will squeeze the tongue 5 between them and the opposite side of the member 4, and thereby firmly hold the member 4 in place upon the tongue 5 and prevent its accidental removal or displacement therefrom.

In the modified form of the impact member 4 illustrated in Figs. 11 and 12, instead of forming the member 4 with a split side, as hereinbefore described, I form the member 4 with opposite sides 9 which, in the normal condition of the member, as illustrated in Fig. 11, are curved or bowed inwardly, so that the normal distance between the sides 9 will be less than the thickness of the projecting tongue 5. When this modified form of the impact member 4 is driven on to the tongue 5, the sides 9 thereof will be sprung outwardly by the tongue, and thereafter, they will squeeze the tongue between them and thereby firmly hold the member in place upon the tongue, as they tend to resume their normal condition.

One side of the free end of the tongue 5 is beveled, at 10, to permit the impact member 4 to be driven on to the same, as will be readily understood; and, the member 4, when it is applied to the body member 3, is driven on to the tongue 5 until the inner or basal end of the member 4 comes into engagement

with the shoulders 6 which prevent further inward movement of the member 5 both while being applied to the body member 2 and afterward when the tool is in service.

The size of the impact member 4 is such that, after it has been driven on to the body member 2 and into engagement with the shoulders 6 thereof, the outer or impact end portion of the member 4 will project beyond the outer end of the tongue 5 and surround and inclose an open space 11, as clearly shown in the drawings.

After the impact member 4 has been driven on to the body member 2, the ends of the inner or basal end of the member 4 project beyond the outer face of the body member 2 to be engaged by a hammer or other suitable instrument and thereby permit the member 4 to be readily driven off from the tongue 5, when it is desired to remove the impact member from the body member.

When the impact member 4 is in place upon the body member 2, the face of the free outer end or bottom of the member 4 forms the impact face which strikes against the material being tamped, and, as this face of the member 4 always surrounds a central, open space, until the outer or impact end of the member 4 is worn down to the outer end of the tongue 5, it will be impossible for the impact end of the member 4, as a whole, to be worn into a sharp, rounded or pointed form, and its character will always be such as to provide an efficient impact surface which will engage the pieces of broken stones, gravel or other material being tamped and drive them into the desired tamped position.

After the outer end portion of the impact member 4 has been worn down to or near the outer end of the tongue 5 of the body portion 2, the worn impact member 4 is removed from the body member 2 and a new impact member from a lot kept on hand for the purpose is driven on to the tongue 5 in substitution for the worn member, as previously explained, and the tamping tool is again ready for service, and little time is lost in changing the impact members.

As the impact members 4, made in accordance with my invention, may be manufactured at little cost, the cost of maintaining the tamping tool in an efficient condition will be slight, and the length of the body member 2 carrying the impact member 4 will remain unimpaired.

I claim:

1. A tamping tool comprising a body member, and a removable impact member engaged with the body member, one of said members having a resilient part sprung from a normal condition and engaging a part of the other member, and said members being held in engagement with each other

by the action of said part in tending to resume its normal condition.

2. A tamping tool comprising a body member, and a removable impact member engaged with the body member, said impact member having a resilient part sprung from a normal condition and engaging said body member and holding said members in engagement with each other in tending to resume said normal condition.

3. A tamping tool comprising a body member having a reduced end portion providing a shoulder at the base thereof, and a removable impact member embracing said portion and being adapted to engage said shoulder, said impact member being movable on said end portion toward and from said shoulder.

4. A tamping tool comprising a body member having a reduced end portion providing a shoulder at the base thereof, and a removable impact member embracing said portion and being adapted to engage said shoulder, one of said members having a resilient part sprung from a normal condition and engaging a part of the other member, and said members being held in engagement with each other by the action of said part in tending to resume its normal condition.

5. A tamping tool comprising a body member having a reduced end portion providing a shoulder at the base thereof, and a removable impact member embracing said portion and being adapted to engage said shoulder, said impact member having a resilient part sprung from a normal condition and engaging said end portion and being held thereon by the action of said part in tending to resume its normal condition.

6. A tamping tool comprising a body member, and a hollow impact member removably engaged with the body member, one of said members having a resilient part sprung from a normal condition and engaging a part of the other member, and said members being held in engagement with each other by the action of said part in tending to resume its normal condition.

7. A tamping tool comprising a body member, and a removable impact member in the form of a band surrounding and engaging the body member, the inner wall of said band substantially conforming to the outer wall thereof in spaced relation thereto.

8. A tamping tool comprising a body member, and a removable impact member in the form of a band surrounding and engaging the body member, said impact member inclosing an open space beyond the body member, the inner wall of said band substantially conforming to the outer wall thereof in spaced relation thereto.

9. A tamping tool comprising a body

member, and a removable impact member in the form of a band surrounding and engaging the body member, said impact member inclosing an open space beyond the body member, and one of said members having a shoulder formed thereon engaging the other member and preventing relative displacement between said members.

10. A tamping tool comprising a body member having a reduced end portion providing a shoulder at the base thereof, and a removable impact member in the form of a band surrounding and engaging said end portion and being adapted to engage said shoulder.

11. A tamping tool comprising a body member having a reduced end portion providing a shoulder at the base thereof, and a removable impact member in the form of a band surrounding and engaging said end portion and being adapted to engage said shoulder, and said impact member inclosing an open space beyond the body member.

12. A tamping tool comprising a body member, and a removable impact member in the form of a band surrounding and engaging the body member, said impact member having a resilient side sprung from a normal condition and engaging said body portion and being held thereon by the action of said side in tending to resume its normal condition.

13. A tamping tool comprising a body member having a reduced end portion providing a shoulder at the base thereof, and a removable impact member in the form of a band surrounding and engaging said end portion and being adapted to engage said shoulder, said impact member having a resilient side sprung from a normal condition and engaging said end portion and being held thereon by the action of said side in tending to resume its normal condition.

14. A tamping tool comprising a body member, and a removable impact member in the form of a band surrounding and engaging the body member, said impact member having a split side sprung from a normal condition and engaging said body portion and being held thereon by the action of said side in tending to resume its normal condition.

15. A tamping tool comprising a body member having a reduced end portion providing a shoulder at the base thereof, and a removable impact member in the form of a band surrounding and engaging said end portion and being adapted to engage said shoulder, said impact member having a split side sprung from a normal condition and engaging said body portion and being held thereon by the action of said side in tending to resume its normal condition.

16. A tamping tool comprising a body

member having a reduced end portion providing a shoulder at the base thereof, and a removable impact member in the form of a band surrounding and engaging said end portion and being adapted to engage said shoulder, said impact member having a split side sprung from a normal condition and engaging said body portion and being held

thereon by the action of said side in tending to resume its normal condition, and said impact member inclosing an open space beyond the body member. 10

In testimony whereof I affix my signature hereto.

DAVID F. VAUGHAN.
